UNITED STATES PATENT OFFICE.

EUGENE M. PLETCHER, OF PHILADELPHIA, PENNSYLVANIA.

INHALER.

Application filed October 19, 1922. Serial No. 595,470.

To all whom it may concern:

Be it known that I, EUGENE M. PLETCHER, a citizen of the United States, residing in the city and county of Philadelphia, State 5 of Pennsylvania, have invented a new and useful Inhaler, of which the following is a specification.

My invention relates to an inhaler adapted to be inserted into and retained in the nostrils, and supply a medicament to the latter for the treatment of a cold, catarrh, hay fever, asthma, influenza, etc., the inhaler being formed with cups or pockets in which the medicament is contained so that the 15 medicament is thoroughly effective by continuous vaporization for the treatment as above.

The present invention is an improvement over that shown in the Letters Patent No. 20 1,231,787, granted to me July 3, 1917, and is designed to remove the outer ends of the medicament in said patent from contact with the membrane or lining of the nose and present in the present device the smooth 25 exterior sides of the cups to said membrane, thus avoiding chafing or cutting of the latter, and causing the continuous vaporization as above stated. The invention is satisfactorily illustrated in the accompanying 30 drawing, but the important instrumentalities thereof may be varied, and so it is to be understood that the invention is not limited to the specific details shown and described, as long as they are within the spirit or 35 scope of the claim.

Figure 1 represents a perspective view partly dotted of the inhaler embodying my invention showing it in applied position.

Figure 2 represents a longitudinal section 40 thereof on line 1—1 Figure 1, on an enlarged scale.

Figure 3 represents a perspective view of the complete device on an enlarged scale.

Figure 4 represents a plan view thereof. 45 Similar numerals of reference indicate corresponding parts in the figures.

I designates a bow of resilient metal, rubber or other suitable material whose limbs are adapted to conform to the shape 50 of the nose septum and to close against the latter to retain the device in the nose.

On the upper ends of said legs and secured thereto are the cups 2 respectively which are closed but slotted at the tops 3 and sides 55 4, and open below as at 5 and adapted to

form pockets to receive wads or cartridges of a medicament of a nature to evaporate and so act on the interior of the nostrils on the bronchial tubes, etc. to treat the same for the ailments above stated. 60

The cartridges are inserted into the cups through the open bottoms of the latter and pressed upwardly thereinto, and owing to small slots being formed in the walls of the cups said walls are rendered resilient so as 65 to exert pressure on the cartridges and so take firm hold of the same and prevent them from dropping out through the bottom of the cups.

As the cups are now charged with the medicament the device is inserted upwardly in the nostrils when the resilient bow engages the sides of the septum of the nose and owing to its resiliency it will frictionally take 70 hold of said septum and so retain the device 75 in the nostrils.

The medicament of the cartridges will now vaporize continuously in the nostrils the vapor then entering the same and so reaching 80 desired places whereby it will cause effective remedial treatment of the ailments above enumerated.

Attention is drawn to the fact that the cups rise from the upper ends of the bow and they have the walls of their outer 85 sides 4 extend in vertical direction and said sides are in the main smooth without liability to injure the membranes of the nostrils.

It is not intended that the cups shall contact with the membranes of the nostrils 90 and so sufficient spaces will be afforded in the nostrils for air to enter the same for breathing purposes.

In practice the bow and cups are formed 95 integral of a single piece of metal or material properly cut and stamped into the respective form thus avoiding joints, and decreasing the cost of manufacture, producing the device of reduced expense.

Having thus described my invention what 100 I claim as new and desire to secure by Letters Patent, is:—

An inhaler comprising a pair of inverted cups the top walls of each of which are slotted T-shaped fashion to provide a yielding cartridge supporting member, a substantially cylindrical cartridge vertically positioned within each of said members, and a bowed spring connecting said cups. 105

EUGENE M. PLETCHER.
